UNITED STATES PATENT OFFICE.

DELMONT LOCKE, OF BROOKLYN, NEW YORK.

BANNER.

SPECIFICATION forming part of Letters Patent No. 496,423, dated May 2, 1893.

Application filed July 28, 1892. Serial No. 441,456. (No model.)

To all whom it may concern:

Be it known that I, DELMONT LOCKE, a citizen of the United States, residing at Brooklyn, in the county of Kings and State of New York, 5 have invented a new and useful Improvement in Banners, of which the following is a specification.

My invention relates especially to banners for political or campaign uses. These banners 10 are usually suspended from a rope hung across a street and consist of cord netting which can be seen through and which do not obstruct the passage of air. These banners bend freely in all directions.

15 My invention relates to a banner to be carried by hand suspended from a pole or which can be hung upon the wall of a dwelling or other building.

20 My invention consists in a banner having a flexible body portion composed of parallel strips of thin wood or reed connected together at intervals by interlacing cords or bands of fabric. This body portion is flexible lengthwise and can bend or be rolled up but it is 25 rigid or unyielding widthwise and the wood strips coming close together it cannot be seen through and what may be behind the banner not being seen, does not detract from the banner. Upon the face of the flexible body portion 30 is secured a painted or lithographed sheet of paper, canvas or the like, said sheet being the portrait or representation of one or more political candidates or the representation of a figure and preferably cut out on the profile 35 thereof. The lower edge of the flexible portion I prefer to make with a border or fringe, preferably of twisted rope of ornamental form, and across the lower part of the flexible portion and between the representation of the 40 political candidate and the border I prefer to place an ornamentally disposed strip of tri-colored bunting or other fabric, the whole being a new article of manufacture.

45 My banner can be rolled up for storage or transportation and unrolled at pleasure.

In the drawings Figure 1 represents my improvement by an elevation, and Fig. 2 shows the detailed construction of the flexible portion.

50 *a* represents the flexible portion. This is composed of parallel strips of thin wood or

reed connected at intervals by longitudinal interlacing and crossing cords or bands similar to matting but of slightly more open character. To the upper edge of this flexible portion *a* are connected rings *a'* at intervals and the bar *b* is threaded through these rings *a'* and a chain or cord *c* whose ends are connected to the ends of said bar *b* is employed to suspend the banner from a pole for outdoor use or from a nail driven in a wall within doors.

d represents a painted or lithographed sheet of paper, canvas or the like, also flexible, upon one face of which is the portrait or representation of one or more political candidates or the representation of a figure, and I prefer to cut the said sheet around the outline or profile of the head and bust of said figure or portrait to remove the surplus material, and 65 this is secured upon the face of the flexible portion *a* and the surface of the flexible portion *a* around the head may be shaded or ornamented in any desired manner.

Along the lower edge of the flexible portion 70 *a* I have shown and prefer to use an ornamental border or fringe *e* composed of twisted rope or similar material, and above this and below the portrait or figure *d* and widthwise across the flexible portion I prefer to place a 75 strip of tri-colored bunting or other fabric *f* ornamentally disposed, the form shown being one of several in which said fabric can be arranged.

I do not limit myself to the use of the strip 80 of fabric *f* or the border *e*, as the same may be changed or dispensed with at pleasure.

I distinctly disclaim such banners as have been made of cord netting with runners for a suspending rope, the portraits of political candidates as well as lettering and ornamentation being sewed to the netting.

I claim as my invention—

1. As a new article of manufacture, a banner consisting essentially of a flexible portion 90 *a* composed of parallel strips of thin wood connected by longitudinal interlacing crossing cords or bands and a sheet of paper, canvas or the like, secured upon the face thereof and whose surface is painted or lithographed to 95 represent a portrait or figure, and a bar suspending device at the upper edge thereof,

substantially in the manner and for the purposes set forth.

2. As a new article of manufacture, a banner consisting essentially of the flexible portion *a*, composed of connected parallel strips of thin wood, the connecting rings or devices *a'*, the bar *b*, the chain or cord *c*, the painted or lithographed portrait sheet *d*, the border

e and fabric strip *f*, substantially in the manner and for the purposes set forth.

Signed by me this 26th day of July, 1892.

DELMONT LOCKE.
